(57) CLAIM

I claim the ornamental design for a strainer with reservoir and magnetic core for compressing canned tuna with opened lid, as shown and described.

DESCRIPTION

FIG. 1 is a perspective view of a strainer with reservoir and magnetic core for compressing canned tuna with opened lid showing my new design;

FIG. 2 is a top plan view thereof;

FIG. 3 is a bottom plan view thereof;

FIG. 4 is a side elevational view thereof taken along line 6—6 of FIG. 2, the opposing side elevational view being identical thereto;

FIG. 5 is a side elevational view thereof taken along line 7—7 of FIG. 2, the opposing side elevational view being identical thereto;

FIG. 6 is a cross-sectional view thereof taken along line 6—6 of FIG. 2;

FIG. 7 is a cross-sectional view thereof taken along line 7—7 of FIG. 2; and,

FIG. 8 is a perspective view showing the strainer with reservoir and magnetic core for compressing canned tuna with opened lid in use; the broken lines depict environmental structure for illustrative purposes only and form no part of the claimed design.
